SNOWMOBILE TRAILER

Carl W. Sherer, 12621 County Road 11,
Burnsville, Minn. 55378

Filed Feb. 28, 1969, Ser. No. 15,974

Term of patent 14 years

Int. Cl. D12—13

U.S. Cl. D14—24

FIG. 1 is a view in side elevation of a snowmobile trailer showing my new design, the side opposite that shown being substantially a mirror image;

FIG. 2 is a view in rear elevation thereof;

FIG. 3 is a view in front elevation thereof;

FIG. 4 is a view in top plan thereof; and

FIG. 5 is a view in bottom plan thereof.

I claim:

The ornamental design for a snowmobile trailer, substantially as shown and described.
